US0D1064866S

(12) **United States Design Patent** (10) **Patent No.:** **US D1,064,866 S**
(45) **Date of Patent:** **** Mar. 4, 2025**

(54) **MOVEMENT SENSOR**

(71) Applicant: **Shenzhen Starlight Dream Technology Co., Ltd.**, Shenzhen (CN)

(72) Inventor: **Tingfeng Xiao**, Shenzhen (CN)

(73) Assignee: **Shenzhen Starlight Dream Technology Co., Ltd.**, Shenzhen (CN)

(**) Term: **15 Years**

(21) Appl. No.: **29/858,119**

(22) Filed: **Oct. 28, 2022**

(51) LOC (15) Cl. **10-04**

(52) U.S. Cl.

USPC **D10/106.6; D10/70**

(58) **Field of Classification Search**

USPC D10/70, 104.1, 118, 106.1–106.9

CPC G08B 13/02; G08B 13/08; G08B 13/1463; G08B 13/2491

See application file for complete search history.

(57) **CLAIM**

The ornamental design for a movement sensor, as shown and described.

DESCRIPTION

FIG. 1 is a front, bottom and right side perspective view of a movement sensor, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the movement sensor, which form no part of the claimed design.

1 Claim, 7 Drawing Sheets
